UNITED STATES PATENT OFFICE

THOMAS R. DAVIS, OF FAIRFIELD, CONNECTICUT, ASSIGNOR TO THE EASTERN MALLEABLE IRON CO., OF BRIDGEPORT, CONNECTICUT, A CORPORATION OF CONNECTICUT

PARKING SIGN

Application filed June 22, 1929. Serial No. 372,883.

This invention relates to new and useful improvements in signs for use upon city streets for indicating the parking regulations as adapted by the local police or municipal authorities.

The object of the invention is to provide a metal sign which can be made of a comparatively few pieces, preferably malleable iron, and in a manner to permit it to be inexpensively finished and attractively painted, so as to be readily seen and read, and whereby the reading matter or a portion thereof may be removed and other signs substituted to more readily adapt its use to changing conditions or locations.

A further object is to provide a sign of the class specified which is particularly adapted for attachment to posts or poles such as are commonly used in the streets for other purposes, and whereby the main body or part of the sign may be more or less permanently secured to the post, while other portions, containing reading matter, which should be changed from time to time, are made removable for the substitution of other sign plates containing different reading matter.

With these and other objects in view, the invention resides and consists in the construction and novel combination and arrangement of parts hereinafter more fully described, illustrated in the accompanying drawings, and pointed out in the claims hereunto appended, it being understood that various changes in the form, proportion, size, and minor details of construction within the scope of the claims may be resorted to without departure from the spirit, or sacrificing any of the advantages of the invention.

Similar characters of reference denote like or corresponding parts throughout the several figures of the accompanying drawing forming a part of this specification and upon which

Fig. 1 shows a front elevation of one form of my invention as shown applied to a portion of a street pole;

Fig. 2 is an enlarged front elevation of one end portion of the sign with attachable sign plate removed;

Fig. 3 is a cross section taken on line 3—3

of Fig. 2 showing the removable sign plate attached; and

Fig. 4 shows a modification of the invention illustrating the same applied to a portable post having but one removable sign plate.

The invention as shown in Figs. 1 to 3 inclusive comprises three cast metal members which are preferably formed of malleable iron, and each include suitable lettering so that they may form separate and individual signs or may be associated to be read together. The lettering as used upon the face of the several parts is preferably formed in the pattern from which the castings are made so that the finished cast metal pieces will include raised and preferably smooth faced letters to facilitate the painting of the faces in colors contrastingly different from that of the main body of the sign.

Referring in detail to the characters of reference marked upon the drawings, 10 represents an upright in the form of an elongated strip or plate-like sign member, having raised edge portions 11 and raised letters 12, which latter may obviously be compiled for the spelling of any appropriate word, as, for instance, the word "Parking" as illustrated in Fig. 1. The upper and lower end portions of this upright as shown in Fig. 1 are of the same special formation which adapts the sign for removable attachment to street posts of varying sizes, and also have means for the removable support of interchangeable sign plates of any preferred shape or design, preferably round and oval in cross section. These end portions of the vertical uprights include a raised base portion 13 having a pocket 14 in its underside with tapered side walls to facilitate the molding of the piece, and further includes aligned diametrically opposed openings 15 and 16 to receive the end portions of an attaching wire 17 that girdles the street pole 18. These wires have their end portions 19 threaded to receive nuts 20 that shoulder against the outer face of the openings 15—15 of the raised end portions 13.

It will thus be seen that a wire of suitable length may be laid around a pole and its two threaded end portions positioned in the two

aligned portions 15 and 16 whereupon the nuts may be tightened to draw the wire and secure the upright to the posts.

These raised end portions 13-13 are further provided with a threaded stud 21 having a square shoulder 22 to fit the correspondingly shaped central hole in the interchangeable sign plates 23 which are removably secured thereto by means of the nut 24. These sign plates are preferably circular in form, having a raised bead 25 around their edge portions and raised letters similar to those used on the other castings, and are preferably of a bowed shape to better conform to the cylindrical face of the post.

In Fig. 4 I have shown the invention applied to a portable type of sign, which is also adapted to be made of malleable iron, and includes an upright 10^a of suitable size and proportions which may or may not have upon it lettering such as the word "Parking", but has a stud formed on its upper end similar to the sign shown in Figs. 1, 2 and 3 for the attachment of the interchangeable sign plates 23 and also has openings for the wire ends. This upright is mounted on a heavy cast metal base 26 constructed like that of the sign shown in Figs. 1, 2 and 3 and adapted to form a portable support for the post and whereby the latter and its attached sign may be moved from place to place as the case may require.

Having thus described my invention, what I desire to secure by Letters Patent is:

1. A sign of the class described, comprising an upright having a raised hollow end portion and aligned openings in opposite sides of said hollow portion to receive wire ends for its attachment to a post, and means for securing sign plate to said raised end portion of the upright.
  2. A sign of the class described, comprising an upright having raised hollow portions at each of its ends, said hollow portions having aligned openings in their opposite sides to receive wire ends for attachment of the upright to a post, a wire to encircle a post and having its ends adjustably mounted in said aligned openings, and means for securing sign plates to said raised hollow end portions.
50. Signed at Bridgeport, in the county of Fairfield and State of Connecticut, this 20th day of June, A. D. 1929.

THOMAS R. DAVIS.
